UNITED STATES PATENT OFFICE.

CHARLES TUCK TOULMIN, OF NEW YORK, N. Y.

WATER HEATER OR BOILER.

SPECIFICATION forming part of Letters Patent No. 521,995, dated June 26, 1894.

Application filed March 21, 1894. Serial No. 504,499. (No model.)

To all whom it may concern:

Be it known that I, CHARLES TUCK TOULMIN, of 165 Broadway, in the city, county, and State of New York, United States of America, 5 have invented certain new and useful Improvements in Water Heaters or Boilers; and I do hereby declare that the following is a full, clear, and exact description of the same.

My invention relates to that class of water-heaters or boilers which may be employed for the production of steam power, for the production of steam for heating purposes in connection with suitable radiators, or for the circulation of hot water through the apartments 15 of any structure which it is desired to warm; and particularly to those which are constructed of separable and interchangeable sections, so that by increasing or decreasing their number, the capacity of the heater or boiler can be readily altered at will.

Among the objects of my improvements are to increase the water-heating surface and to arrange for varying the same at will, to improve the circulation, to provide for conveniently 25 cleaning the flues, to facilitate the heating, to enable any section to be readily removed and replaced without disconnecting the other parts, and to otherwise variously simplify and improve the construction.

To this end, my invention comprises various novel features of construction; and in order that the invention may be clearly ascertained, I shall first describe in detail the mode in which I carry the invention into 35 practice and then point out its several features in the claims.

Reference is to be had to the accompanying drawings, forming part of this specification, in which—

Figure 1 is a side elevation of a sectional water heater or boiler embodying my invention. Fig. 2 represents the same in cross-section on the line 2—2 Figs. 1 and 3. Fig. 3 represents the same in central longitudinal section. Fig. 4 is a perspective view of one of the sections of the same. Figs. 5 and 6 are vertical sectional views of two adjoining sections of the same. Fig. 7 is an enlarged detail sectional view illustrating the improved 45 coupling connecting each section with the collecting pipe. Fig. 8 is a broken perspective view of a tubular water-grid used in the

combustion chamber for facilitating the heating. Fig. 9 is a front elevation of the heater or boiler. Fig. 10 is a plan view of one of 55 the grate-sections.

Like parts are designated by the same letters of reference in all the figures.

I construct the body of the heater or boiler of a variable number of vertical transverse 6c hollow sections A, by preference of cast iron, alternating regularly with and closely abutting similar vertical transverse sections B, differing only slightly therefrom as hereinafter described, a vertical water-back section 65 C, and a front plate D, which I in some instances may cast integrally with the front section A.

The various sections A, B, C and D correspond exteriorly and are rigidly bound together by outside projecting lugs E and bolts F, which may connect all the sections as shown, or be in number, each to connect two adjoining sections if preferred.

Each section A is cast with vertical side 75 water-legs G G', connected and communicating at their upper ends by a transverse steam and water-head H having a steam dome H', a short distance above their lower ends by a transverse water-waist I, and between the 8c head H and waist I, which are of the same thickness throughout, by a water-bridge J of about half the thickness of the said head and legs, and separated from the head and waist by the spaces K and L respectively. 85

Each alternating section B is formed like the sections A just described, save that its water-bridge J' is continued upward into its head H, so as to leave no opening therebetween. The tops J² of the water-bridges J of 90 the sections A, I make V-shaped, as shown, to facilitate the upward and outward circulation of water from said bridges J into the water-legs G G'.

The abutting water-legs G G' and water-waists I of all the combined sections A and B, and the back section C, form the imperforate water-walls, water-roof and water-back, respectively, of the combustion chamber K, which, as I omit, or form an opening L through 100 the water-waist of the last section A, communicates at its back with the vertical space or flue between the water back C, and the next adjacent water-bridge J.

I provide an adjustable cut-off L' for each space or opening L between the water-bridge and water-waist of each of the sections A and B, and normally close all the cut-offs L' in the 5 sections A, and open those in the sections B. For the purpose of simultaneously adjusting these two sets of alternate cut-offs L', I connect them on the outside of the boiler or heater with continuous operating rods M and M', 10 as indicated in Fig. 1.

All the sections A and B are in addition provided with inside ledges N below the water waists I, to support the grate O, (which may be sectional as shown,) above the ash 15 pit O', and with the ledges P immediately below the waist I, on which I rest horizontally a removable tubular water grid Q (shown in Fig. 8) composed of hollow transverse end bars Q' connected medially by longitudinal 20 water-tubes Q² and on each side by guide rails Q³ whereby the grid Q will slide easily on the ledges P into and out of the combustion chamber.

The front of the combustion chamber K is 25 closed by a double door R R' in the face plate D, the outer door R being large enough and opened only to permit the passage of the removable grid Q, the inner door R' being the one employed for replenishing the fire.

30 The domes H' of the water heads H of all the sections A, B and C are severally connected by a peculiar form of coupling S, shown in detail in Fig. 7, to a collecting pipe T running over the top of the heater or boiler, by 35 which the steam or hot water from all the water sections A, B and C is supplied to the circulating pipe T'.

The water-legs G G' of all the sections A, B and C are likewise connected at their feet 40 by like couplings S to collecting pipes U, by which the cold or condensation water from the circulating system is returned to the bottom of all the said water sections. The said couplings S each consist of threaded coupling-sleeves S' S² formed on the collecting pipe as U, and on the water-section as A, respectively, a head S³ having its coupling ends S⁴ and S⁵ threaded oppositely to the respective coupling sleeves S' and S² and couplers S⁶ 45 and S⁷, each of which has its ends oppositely threaded to engage the opposing sleeves S' and S² and the ends S⁴ and S⁵, so that by simply unscrewing the couplers S⁶ S⁷, they will be disconnected simultaneously from the collecting pipe and the water-sections, as A, and 55 thus permit the renewal of any water-section A, without disturbing any of the other sections or their connections. The opposite ends of the removable water grid Q are also connected, as indicated in dotted lines, by detachable couplings Q⁴ and Q⁵ and pipes Q⁶ 60 and Q⁷ respectively to the supply pipe T and one of the return pipes W. The removable water grid Q is thus employed to hasten the 65 initial circulation, as the flames play first thereon and cause the hot water therein to

ascend almost immediately through its supply pipe Q⁶, the cold water entering at the same time at the other end through the return pipe Q⁷. The flames also play through 70 the grid Q upon the cellular water roof of the combustion chamber K formed by the water waists I, from which they also rebound upon the upper side of the grid Q, and they also play upon the cellular water walls of the 75 combustion chamber K, so that the water in said roof and walls is heated and ascends in the water legs G G'.

The products of combustion ascending from the back of the combustion chamber K 80 through the roof opening L as before described, play upon the water back C, and, the cut-offs L' in the alternate water-sections A being closed, are forced to ascend in the vertical flue formed between the water back and the next adjacent water-bridge J, thence between said water-bridge and the corresponding water-head H, and down between said bridge and the next bridge J', and then beneath the latter, and so on through the vertically zig-zag flue thus formed between the water-bridges, heads and waists, until the escape flue W is reached.

The inner sides of the water-back C, water-legs G G' and water-heads H, and both sides 95 of the water-bridges J J' and water-waists I of all the sections are thus impinged upon by the heated products of combustion, by which an exceptionally large and effective heating surface is obtained. The heated water and steam ascends from the water-legs, 100 bridges and heads into the domes H', and thence through the collecting supply pipe T into the circulating system, whence the cold water is returned as before described. 105

By opening all the cut-offs L' the products of combustion may be shunted from the vertically zig-zag flue and into the straight base flue thus formed beneath all the bridges J J', to give a direct draft for firing, and in a like manner this base flue, which is provided with a door V in the front plate D, can be made accessible therethrough for cleaning the flues, the accumulations in all of which will from the nature of the construction be deposited 115 in said base flue.

Having thus described my invention, what I claim, and desire to secure by Letters Patent, is—

1. A water heater or boiler constructed of a series of cast vertical sections, each formed with side water-legs G G', a transverse steam and water-head H, a transverse water-waist I, and a transverse water-bridge of less thickness than the water-legs and head, the combined spaces below the water-waists I constituting the combustion chamber, and the vertical spaces between the water-bridges a succession of vertical flues, connected with the back of the combustion chamber, a grate 120 placed in said combustion chamber below the water waists I and supply and return pipes 125

connected respectively with the head and water-leg of each section, substantially as herein shown and described.

2. A water heater or boiler constructed of a series of vertical sections, each formed with side water-legs G G', a transverse steam and water-head H, a transverse water-waist I, and a transverse water-bridge J or J' of less thickness than the water-legs, the combined spaces below the water-waists I, constituting the combustion chamber, and the alternate sections formed with spaces respectively between the water-bridges J and the water-heads H, and between the water-bridges J', and the water-waists I, said spaces and the vertical spaces between said water-bridges to constitute a vertically zig-zag escape flue connected with the back of the combustion chamber, and supply and return pipes connected respectively with the head and leg of each section, substantially as herein described.

3. A water heater or boiler constructed of a series of vertical sections, each formed with side water-legs G G', a transverse steam and water-head H, a transverse water-waist I, and a transverse water-bridge J or J' of less thickness than said water-legs, the combined spaces below the water-waists I constituting the combustion chamber and the alternate sections formed respectively with spaces between the water-bridges J' and the water-waists I, and both above and below the water-bridges J,

said spaces and the vertical spaces between said water bridges to form a vertically zig-zag escape flue, cut-offs in the spaces below the 35 water-bridges J, means for operating said cut-offs, and supply and return pipes connected with the head and leg, respectively, of each section, substantially as herein described.

4. The sectional water heater or boiler herein described having water-legs G G', and abutting water-waists I forming the sides and top respectively of the combustion chamber, said water-legs being formed with ledges P, in combination with a removable tubular water-grid 45 Q sliding on the ledges P above the grate and below the water-waists I and couplings detachably connecting said grid at opposite ends with the supply and the return pipes respectively, as set forth.

5. In a sectional water heater or boiler as described, the combination with each water-section and the collecting pipe provided with threaded coupling sleeves S², S', of a bend S³ having coupling ends threaded oppositely to 55 the respective coupling sleeves S² S', and couplers S⁶ S⁷, each having its ends oppositely threaded, substantially as and for the purpose hereinbefore set forth.

New York, N. Y., January 25, 1894.

CHARLES TUCK TOULMIN.
